FIG. 2

FIG. 3

FIGURE 1 is a side elevational view of a bottle, showing my new design;

FIGURE 2 is a side elevational view thereof taken from the right side of FIGURE 1; and

FIGURE 3 is a top plan view thereof.

The sides not shown are the same as the sides shown. Six vertical rows of oval indentations are equally spaced around the upper portion of the bottle. Each vertical row comprises three ovals which diminish in size from the top to the bottom of the row.

The unstippled portions of the bottle contrast in appearance with the stippled portions thereof in FIGURES 1 and 2 of the drawing.

The dominant features of my design reside in the portions shown in full lines.

I claim:

The ornamental design for a bottle, substantially as shown and described.
